UNITED STATES PATENT OFFICE.

NORTON A. NEWDICK, OF COLUMBUS, OHIO.

COAL-LOADING MACHINE.

1,362,889.

Specification of Letters Patent. Patented Dec. 21, 1920.

Application filed May 10, 1916. Serial No. 96,723.

To all whom it may concern:

Be it known that I, NORTON A. NEWDICK, a citizen of the United States, residing at Columbus, in the county of Franklin and 5 State of Ohio, have invented certain new and useful Improvements in Coal-Loading Machines, of which the following is a specification.

This invention relates to coal loading machines and is directed particularly to that 10 class of loading machines used in a mine to load the coal into the mine cars after it has been blown down.

The main object of my invention resides 15 in the provision of a machine of this type whose construction and relative arrangement is such that it may be readily utilized in many types of mines to remove the coal from the mine floor and deposit it into a 20 suitable mine car. To this end, my invention resides broadly in the combination of a pair of separate trucks, one having mounted thereon a gathering conveyer mounted adjacent its rear end to swing about a vertical 25 axis and the other being provided with a hopper and a discharging conveyer leading out of it, the swinging axis of the front conveyer and the hopper being so located with respect to each other upon their separate 30 trucks that when the two trucks are brought into working position one with the other, the hopper will be in receiving position with relation to the discharge end of the gathering conveyer for all positions of angularity 35 of the gathering conveyer with respect to the front truck and for all positions of angularity of the two trucks with respect to each other and for all positions of angularity of the two conveyers with respect to 40 each other. By this arrangement, a loading machine capable of being applied to various uses other than coal loading is provided. By the use of separate trucks, the machine may be easily proportioned to facilitate the 45 transportation without teetering or jumping the rails. Likewise, should one unit be temporarily out of operation, the idle investment is considerably less than where the entire structure is mounted upon a single 50 truck.

Among the other objects of my invention is the provision of a structure whereby the gathering conveyer is mounted adjacent its rear end to permit of its various movements and adjustments.

The preferred embodiment of my invention is shown in the accompanying sheets of

drawings, in which similar numerals refer to similar parts throughout the several views, and in which:

Fig. 1 is a view in side elevation of my improved type of coal loading machine,

Fig. 2 is a top plan view of the structure shown in Fig. 1,

Fig. 3 is a view in side elevation on a 65 slightly larger scale of the gathering conveyer mechanism,

Fig. 4 is a top plan view of the structure shown in Fig. 3,

Fig. 5 is an enlarged detail view showing 70 the manner of supporting the gathering conveyer on its supporting truck,

Fig. 6 is a view in side elevation showing 75 the discharge conveyer and its driving mechanism,

Fig. 7 is a top plan view of the structure shown in Fig. 6,

Fig. 8 is an enlarged section taken on line 8—8 of Fig. 4,

Fig. 9 is an enlarged section taken on line 80 9—9 of Fig. 4,

Fig. 10 is a section taken on line 10—10 of Fig. 8,

Fig. 11 is an enlarged section taken on line 11—11 of Fig. 4,

Fig. 12 is an enlarged detail view partially in section of a portion of the conveyer chain and its guide,

Fig. 13 is a section taken on line 13—13 of Fig. 12, and,

Fig. 14 is a section taken on line 14—14 of Fig. 6.

My coal handling apparatus comprises essentially two interacting units shown in assembled relation on Sheet 1 and shown 95 separately on Sheets 2 and 3.

The gathering conveyer and its driving structure is shown in detail on Sheets 3, 4 and 5 and comprises a drive sprocket 1 and an idle or tail sprocket 2, over which a chain 100 3 passes. This chain is equipped with a plurality of laterally extending flights shown at 4, which are designed to dig themselves into the coal heap and carry the coal up one side of the conveyer pan or trough, 105 which is designated in its entirety by the reference numeral 5. This chain, in addition to being guided by the sprockets 1 and 2 is also guided by the channel guideways 6, the conveyer itself being provided with a 110 depressed horizontally extending front end nose portion 7, a rearwardly extending tail portion 8 and an intermediate inclined portion 9. The chain guideways located be-

tween the portions 7 and 9 are provided with a curved casting 10 into which a plurality of rollers 11 are rotatably journaled to lessen the amount of friction in causing 5 the chain to pass the angle formed. A similar arrangement is shown at 12 as being located between the portions 9 and 8 of the conveyer frame. It will of course be understood that when the jack post is set up on 10 the other side of the mine room and the conveyer is bodily swung thereby in the opposite direction, the direction of travel of chain 3 is reversed so that the movement of the flights across the nose 7 will be in the 15 direction of bodily movement of the conveyer. It is manifest that this involves merely the reversal of motor 17 in a usual and well known way.

This entire conveyer structure is supported 20 upon a four-wheeled truck comprising the side pieces 13, axles 14 and 15 and the track wheels 16. Between the axles 14 and 15 there is suitably supported a power unit or driving motor 17, on the outer end of the 25 armature shaft of which is mounted a pinion 18. This pinion 18 meshes with a large spur gear 19 rotatably mounted upon a shaft 20, which shaft is shown in detail in Fig. 11. This shaft 20 is also provided with a friction clutch controlling the various movements of the gathering unit and which clutch comprises the slidable member 21 and the stationary member 22. The slidable member is controlled by the lever arm 23 pivotally 30 mounted at 24 upon the motor casing and being pivotally connected at its upper end as is shown at 25 with the control rod 26, which latter passes out through the side frame and is provided at its outer end with an operating handle 27 within the ready grasp of the operator. On the sleeve 28 of the stationary clutch portion 22, I have rigidly secured a sprocket wheel 29 which sprocket is in line with a sprocket 30 rigidly secured to the hub 45 31 of a bevel gear 32 rotatably supported on the axle 16, this latter structure being shown in detail in Fig. 9. This bevel gear in turn meshes with a bevel pinion 33 located on the vertical shaft 34. This shaft 34 is rotatably 50 journaled in a yoke member designated 35, which yoke member is provided with depending legs 36 having bearing portions 37 rotatably mounted on the axle 15 as shown more clearly in Fig. 9. The upper end of 55 the shaft 34 carries the drive sprocket 1 and through the drive connections just described, the conveyer as a whole may be set in operation by simply shifting the two clutch parts 21 and 22 in engagement with 60 each other.

It is by means of this yoke member, that the conveyer as a whole and the conveyer pan 5 specifically, is mounted to sweep the mine floor or, in other words, is mounted to 65 swing about a vertical pivot. The upper

portion of the yoke member 35 is provided with a shoulder 38 upon which the bearing member 39 rests. The conveyer pan 5 is itself rigidly connected to this bearing member through the medium of the rivets shown 70 at 40 and further, the underside of this pan at this end of the conveyer is provided with an arcuate guide member 41, this guide member being circular with the exception of the open or cut-away portion 42 of the rear end 75 of the pan as is shown in Fig. 4, through which the coal is discharged. A substantially Z-shaped slide member 43 mounted upon bosses 44 of the arms of the yoke member, co-operates with the guide member 41 to 80 give the conveyer pan a substantial bearing at some considerable distance from its rotative center or from the shaft 34. This arrangement just described, permits the conveyer as a whole to sweep the mine floor or 85 pivot about a vertical center which happens to be the shaft 34 and it also permits this conveyer to be swung about a horizontal pivot which, in this case, is the axle 15. This swinging about the horizontal axis is 90 desirable in that it permits the elevation of the front or nose portion of the conveyer to permit its ready transportation from place to place in the mine. The rear portion of the yoke member 35 is also provided with a 95 pivoted dog 45 which, when the conveyer is in its operative position as is shown in Fig. 3 engages the edge of a bolster 46 forming a portion of the supporting truck. This arrangement is provided to relieve the yoke 100 member of undue strain as the conveyer is being forced into the coal heap. When the conveyer is forced into the coal heap, the natural tendency would be to cause a pivoting about the axle 15, and, therefore strain 105 the connections between the two members 41 and 43. It is to relieve this strain that the dog 45 is provided, it being, of course, understood that this dog is released when it is desired to elevate the front end of the conveyer. 110

The mechanism for causing this gathering conveyer to sweep the mine floor will now be described. A jack post or other temporary anchoring means such as shown at 47 is 115 provided and set up adjacent one wall of the mine room or entry. Engaging this jack post is a hook 48 onto which the cable 49 is connected. This cable passes over a pulley 50 secured to the frame portion of the section 9 of the conveyer through the medium of either of the eye bolts 51 and from here it passes rearwardly and is connected with the winding drum 52 mounted on the axle 14 as is shown in Fig. 8. This drum is provided with a laterally projecting sleeve 53 onto which the half 54 of a friction clutch is 120 rotatably mounted. The other half of this clutch is designated 55 and is slidably keyed to the sleeve and is controlled in its move- 125 130

ment by means of the arm 56 pivoted at its lower end as is shown at 57 and provided with a shifting yoke 58. To the upper end of this arm the operating rod 59 is pivotally connected as shown at 60 and by operating this rod 59 through the medium of a handle 61 projecting out through the side frame, the friction clutch may be thrown in or out. The portion 54 of this last named friction 10 clutch is provided with a sprocket 62 which sprocket is in line with a sprocket 63 rigidly secured to the shaft 20 on which the main friction clutch is mounted, so that whenever the friction clutch on this shaft 20 is in, 15 the sprocket 63 rotates. A chain 64 connects the two sprockets 63 and 62 and, therefore, after the friction clutch on the shaft 20 is thrown in, this chain 64 is set in operation to rotate the portion 54 of the friction clutch 20 on the shaft 14 and when then the operating handle 61 is grasped to bring the two parts 54 and 55 of the friction clutch on the axle 14 into engagement, the winding drum 52 is also set into operation to wind up the cable 25 49 and by the shortening of the cable length in this manner, the gathering conveyer as a whole is drawn across the mine floor about its vertical pivot 34. When a sweep across the entire floor has been made, the jack post 30 may be removed and set up on the other side of the mine room, the cable extended and the operation repeated.

In order to automatically prevent the conveyer from forcing itself out of the coal heap after it has been thrown into the same by the operation just described, I have provided one end of the drum with a ratchet face 65, Fig. 10, in connection with which the dog 66 operates. This dog is pivoted as 40 at 67 to the side of the motor frame and as the drum 52 is rotated, the dog runs idle, but upon stopping of the winding action, this dog 66 drops into engagement with one of the teeth on the ratchet wheel 65 and, 45 therefore, prevents reverse rotation of the drum 52. It will be understood that the flights forcing their way into the coal heap have a tendency to push the front end of the conveyer in a direction opposite from that 50 in which it was pulled by the cable and it is, therefore, necessary to lock the conveyer in whatever position of adjustment it may have been placed by the winding up of the cable. This is automatically accomplished 55 by the dog 66 and the ratchet wheel 65. Upon shifting of the jack post and the extending of the cable, it will be understood that the clutch sections 54 and 55 are out of engagement so that the drum is free to rotate on the axle 14. Therefore, by manually 60 releasing the dog 66, the cable may be again extended.

In order to elevate the front end of the gathering conveyer, this same cable and 65 winding mechanism is employed. The hook

is disengaged from the jack post and is attached to the arm 68, Fig. 3, which latter is pivoted at its lower end as at 69 to the truck or conveyer support. The upper end of this arm is provided with a roller 70 and the 70 arm is itself slightly longer than the shortest distance between its pivot point 69 and the underside of the conveyer framework. The arrangement is also such that the roller end of this arm 68 operates on the underside of the conveyer framework, as shown in Fig. 3. After the cable hook has been attached to the arm 68, the winding mechanism may be set in operation to shorten the 75 cable length and this action causes the 80 swinging of the arm 68 about its center 69 to elevate the conveyer by swinging it about its horizontal pivot 15. The action of the dog 66 is the same to automatically lock the drum against reverse rotation after the 85 winding operation is stopped and, therefore, the conveyer is held in any position of elevation at the time the driving clutch on the axle 14 is thrown out of engagement.

The manner of driving this gathering 90 conveyer upon the mine tracks, will now be described. The main drive shaft 20, as is shown in Fig. 11 is provided with a jaw clutch, the movable section of which is designated by the reference numeral 71 and is 95 rigidly secured to the shaft 20 by means of a sliding key engagement and the other or loosely mounted section of which is designated 72. This section 72 is formed with a spur gear face 73 of a size to mesh with the 100 gear 74 rigidly secured to the axle 15. Therefore, when the friction clutch upon the shaft 20 is thrown in, this shaft is set in operation and by moving the keyed section 71 of the jaw clutch into engagement 105 with the section 72, the two gears 73 and 74 are set into operation, which causes the axle 15 to rotate to in turn rotate the drive wheels 16. The movable section 71 of the jaw clutch is controlled through the medium of the 110 control rod 75 pivoted at one end as shown at 76 to the arm 77. This arm is pivoted intermediate its ends as at 78 to a bracket 79 carried by the truck framework and operatively engages the movable clutch section 115 71 as is shown at 80.

From the foregoing description, it will be apparent that I have provided a type of gathering mechanism capable of accomplishing all the necessary movements, that of 120 transporting itself about the mine floor, swinging about a vertical pivot to sweep the mine floor, and elevating its front end to clear the track construction to facilitate its more ready transportation.

However, the open portion 42 of the conveyer pan changes its position by the sweeping movement of the conveyer and, therefore, the discharge point is not always in 125 central alinement with the conveyer when 130

in the position shown in Fig. 4. This is due to the fact that the center of rotation is about the drive sprocket shaft and, therefore, should a mine car be moved into a position to receive the discharged coal, this coal would only fall into the mine car when the conveyer was in the central position shown in Fig. 4. To overcome this, I have provided the discharging conveyer shown in detail in Figs. 6 and 7. This conveyer comprises a pair of endless chains 81 between which flights 82 are secured and operates out of the base of a hopper 83. This hopper as well as the conveyer and its supporting framework is mounted upon a truck designated generally by the reference numeral 84 and shown as being supported upon four track wheels 85, the latter being mounted upon axles 86 and 87. The hopper proper is mounted to be relatively stationary with the truck frame as is shown in detail in Fig. 14 wherein its sides are shown as being rotatably fitted over collars 91* to which the sides 91 of the conveyer frame are secured. The under portion of this hopper further rests on the end frame of the truck as is shown at the point designated 89 and because of its weight, this hopper always maintains this relative position with the frame no matter what may be the position of the conveyer itself. The lower ends of the side frames of this conveyer are rotatably journaled on the axle 86 as is shown and are further provided with upstanding ends 91 to overlap the rearwardly extending portions 92 of the hopper proper. This sliding arrangement between the sides of the hopper and the sides of the conveyer frame is provided to accommodate the structure to the pivotal movement of the conveyer as a whole. The bottom or trough portion shown at 93 coöperates with the flights in moving the coal out of the hopper to its point of discharge and is likewise movable with the conveyer as it swings about its pivot 86 inasmuch as it forms a rigid part of the conveyer frame. The conveyer chains themselves pass over tail sprockets 94 mounted on the axle of the truck 86 and head sprockets 95 mounted on a head shaft 96. The rear portion of the discharge conveyer is so proportioned that it lies substantially parallel with the mine floor when in its operative position as shown in Fig. 6 and extends over the same after the manner illustrated in Fig. 1.

From the arrangement thus far described, it will be apparent that the hopper 83 is so proportioned to receive coal discharged from the gathering conveyer, no matter what may be the position of this conveyer as regards movement about its vertical center. From here the coal is conveyed by means of the discharging conveyer into the mine car and inasmuch as the discharging conveyer never changes its relative position as regards a swinging movement about a vertical pivot, it follows that this conveyer always stands in central alinement with the center of the track and is, therefore, always in a proper position of discharge over the mine car. By means of the rearwardly extending portion as is shown in the drawings, the car may be loaded from its front end and gradually pulled forward by a mine locomotive or any other means as the coal piles up. In addition, the trimmer may pile the coal to a level in the car above or equal to that occupied by the mine car itself as it is pulled forward. It will be observed that the bottom 93 over which the flights 82 travel consists of a plate comprising a sharply inclined portion which constitutes a substantial part of the bottom as well as the rear wall of the hopper proper and that this sharply inclined portion merges into a substantially horizontal portion, which projects rearwardly beyond the truck 84. An important advantage arises from this construction as follows: Frequently very large lumps of coal are discharged into the hopper. If these lumps become securely engaged with the flights they are carried up the sharply inclined portion or rear wall and out of the hopper. If insecurely engaged with a flight they fall back into the hopper. Thus the provision of the sharply inclined portion in conjunction with traveling transverse flights, the whole associated with a hopper one wall of which is formed by said sharply inclined portion assures that no huge lumps will leave the hopper until they become sufficiently engaged by a flight, it being manifest that if such engagement is firm and secure enough to cause the lump to be lifted against the force of gravity from the hopper it will be secure enough to insure the proper conduct of the lump to the discharge end of the conveyer. The importance of this will be appreciated when it is understood that throughout the operation of the machine miners are working about it. A large lump of coal toppled over the side of the discharging conveyer because of its insecure engagement with a flight would be likely to kill or injure a workman.

The manner of driving this discharging conveyer is as follows: A motor 97 is suitably supported on the truck and is provided with a drive pinion 98 meshing with a drive gear 99 mounted on a shaft 100 rotatably journaled in the truck frame. This shaft is also provided with a sprocket 101 in alinement with a sprocket 102 over both of which a chain 103 passes. The sprocket 102 is mounted on a shaft 104 and carries a second sprocket 105 in alinement with a sprocket 106 carried by the head shaft 96 over which the driving chain 107 passes. Thus, when the motor is set in operation, the

conveyer as a whole, is driven by the driving arrangement just described.

When transferring the conveyer from place to place about the mine, it is desirable 5 to lower the upper portion in order to give more clearance or head room and inasmuch as this conveyer frame is pivotally mounted about the axle 86, this may be done in the following manner. A pair of toggle links 10 108 are pivoted respectively to the truck frame and the conveyer support and hingedly connected together as shown at 109. At this connection 109, I have attached a chain 110 which is designed to be wound 15 on a drum 111 which may be hand operated by means of the crank 112. This crank is held against reverse motion by means of the pivoted dog 113. The chain 103 passing over sprockets 101 and 102 is of such length 20 that it attains its proper tautness when the upper portion of the conveyer is substantially parallel with the mine floor and the slack which occurs when the conveyer is lowered is of no consequence, inasmuch as 25 the conveyer is not driven when in such lowered position.

From the foregoing description, taken in connection with the accompanying sheets of drawings, it will be apparent that I have 30 provided a type of coal handling machine which is particularly adapted for many types of mines. The machine operates in a minimum of head room and by means of the rearwardly extending portion of the dis- 35 charging conveyer, this conveyer may be on a level practically with the level of the mine car, reliance being had on the attendant or trimmer for suitably piling the coal after the car has been gradually pulled forward. 40 Also, this arrangement permits the switching of a loaded car and the bringing of an empty without stopping the operation of the gathering conveyer, the coal gathered in the meantime being deposited in the hopper 83 45 and when the empty car is brought to position, the discharging hopper may again be set in operation. All the various advantages outlined and those which must be apparent are attributable in a large sense to the par- 50 ticular relationship which must necessarily be established between the vertical swinging axis of the gathering conveyer with respect to the hopper for all of the various relative positions of the two units with respect to 55 each other so that the discharge end of the gathering conveyer will always be in its proper discharging position with respect to the hopper.

What I claim, is:

60 1. In a loading machine of the character described the combination with a front truck and a rear truck adapted to travel upon and be guided by a mine car track and capable of moving to varying positions of horizon- 65 tal angularity with respect to each other, of a gathering conveyer mounted on the front truck to have a bodily horizontal swinging movement about a vertical axis adjacent the rear end of said truck, said gathering conveyer comprising a pan and flights 70 mounted to travel with respect to said pan to convey material thereover and which flights sweep horizontally and laterally across the front of said pan and horizontally and laterally through the material being 75 gathered, a hopper located at the front of the rear truck and a discharging conveyer leading out of said hopper, the vertical axis of said gathering conveyer and said hopper being so located with respect to each other 80 upon their separate trucks that when the two trucks are brought into working position one in the rear of the other the hopper will be in position to directly receive material discharged from the rear end of the 85 gathering conveyer throughout all positions of angularity of the gathering conveyer with respect to the front truck and throughout all positions of angularity of the two trucks with respect to each other and all positions 90 of angularity of the two conveyers with respect to each other.

2. In a loading machine of the character described the combination with a front truck and a rear truck adapted to travel upon and 95 be guided by a mine car track and capable of moving to varying positions of horizontal angularity with respect to each other, of a gathering conveyer comprising a pan includ- 100 ing an inclined portion and a depressed substantially horizontal front end portion which merges into the inclined portion, means for mounting said pan on the front truck to have a bodily horizontal swinging movement about a vertical axis adjacent the rear end 105 of said track whereby the front end of the pan is caused to have a horizontal swinging movement back and forth over the surface from which material is being gathered, an endless chain carrying transverse flights 110 movable over the surface of said pan and guided at the front end of said pan about a substantially vertical axis, whereby said flights are caused to sweep horizontally and laterally through the material being gath- 115 ered, a hopper located at the front of the rear truck and a discharging conveyer leading out of said hopper, the vertical axis of said gathering conveyer pan and said hop- 120 per being so located with respect to each other upon their separate trucks that when the two trucks are brought into working position one in the rear of the other the hopper will be in position to directly receive ma- 125 terial discharged from the rear end of the gathering conveyer throughout all positions of angularity of the gathering conveyer with respect to the front truck and throughout all positions of angularity of the two trucks with respect to each other and all positions 130

- of angularity of the two conveyers with respect to each other.
3. A structure as recited in claim 1 wherein the gathering conveyer is also mounted 5 for bodily swinging movement about a horizontal axis.
4. In a loading machine of the character described, a gathering conveyer comprising traveling flights operable in both directions 10 and a pan associated therewith comprising slides for conveying the material when the flights are run in either direction, a front truck, means for pivotally mounting the gathering conveyer upon the front truck to 15 adapt its front end to swing horizontally back and forth across a mine floor and, in conjunction with the flights to gather material in both directions, a rear truck, said trucks being adapted to travel upon and be 20 guided by a mine car track and being capable of movement to varying positions of angularity with respect to each other the point of pivotal mounting of the gathering conveyer and said hopper being so located with 25 respect to each other upon their separate trucks that when the two trucks are brought into working position one in the rear of the other the hopper will be in position to directly receive material discharged from the 30 rear end of the gathering conveyer throughout all positions of angularity of the gathering conveyer with respect to the front truck and throughout all positions of angularity of the two trucks with respect to 35 each other an all positions of angularity of the two conveyers with respect to each other.
5. In a coal loading machine, a gathering conveyer including a pan whose going and return sections are at the same elevation, 40 a truck, a member pivotally supported on said truck to swing about a horizontal axis, said member being provided with a vertically extended bearing portion, a head shaft passing through said bearing portion and 45 into said pan, a sprocket on said head shaft located in said pan, and means for rotatably supporting the rear portion of said conveyer pan on said member to swing about a vertical pivot.
- 50 6. In a coal loading machine, a gathering conveyer including a pan whose going and return sections are at the same elevation, a truck, a member pivotally supported on said truck to swing about a horizontal axis, said 55 member being provided with a vertically extending bearing portion, a head shaft passing through said bearing portion and into said pan, a sprocket on said head shaft located in said pan, and means for rotatably supporting the rear portion of said 60 conveyer pan on said member to swing about a vertical pivot, and additional releasable means for preventing said member moving rearwardly about its horizontal pivot.
7. In a coal loading machine, a gathering 65 conveyer including a pan whose going and return sections are at the same elevation, a truck, a member pivotally supported on said truck to swing about a horizontal axis, said member being provided with a vertically ex- 70 tends bearing portion, a head shaft passing through said bearing portion, a sprocket on said head shaft, said conveyer pan being adapted to swing about said shaft as a center, and means carried by said member at a 75 distance from said shaft for preventing relative separation between said member and said pan when said member is swung rearwardly about its horizontal axis and at the same time permitting swinging about its 80 vertical axis.
8. A coal loading machine comprising a gathering conveyer, a truck, a member pivotally supported on said truck to swing about a horizontal axis, said member being 85 provided with an upwardly extending neck portion, means for rotatably supporting the rear portion of said conveyer about the upwardly extending neck portion, and releasable means operatively engaging the rear 90 portion of said conveyer and also said truck to prevent swinging of said conveyer about its horizontal pivot.
9. In a coal loading machine, a pair of 95 separate trucks, a gathering conveyer mounted on one of said trucks, a discharging conveyer capable of a pivotal movement about a horizontal axis mounted on the other truck, and a hopper arranged to be located beneath the discharge end of said gathering 100 conveyer and carried by said second named truck out of which said discharging conveyer operates, said hopper being formed of relatively movable sections to permit the adjustment of said discharging conveyer 105 about its horizontal axis without materially destroying the relationship between the hopper and the discharge end of the gathering conveyer.
10. In a loading machine of the character 110 described, a gathering conveyer whose going and return sections are at the same elevation, a wheeled supporting truck, means for supporting the rear end of said conveyer thereon to enable it to swing about a 115 vertical axis, and means for in turn supporting said first named means from said truck at a position in a substantially vertical transverse plane passing through the rear wheel center of said truck to permit up and 120 down movement of the front end of said conveyer.

In testimony whereof I affix my signature in presence of two witnesses.

NORTON A. NEWDICK.
